Kenneth E. Smith, Coronado, and Alexander G. Tsongas, San Diego, Calif., assignors to Consolidated Vultee Aircraft Corporation, San Diego, Calif., a corporation of Delaware

Application July 9, 1946, Serial No. 131,406

Term of patent 7 years

(Cl. D71—1)

To all whom it may concern:

Be it known that we, Kenneth E. Smith, a citizen of the United States and a resident of Coronado, in the county of San Diego and State of California, and Alexander G. Tsongas, a citizen of the United States and a resident of San Diego in the county of San Diego and State of California, have invented a new, original, and ornamental Design for an Airplane, of which the following is a specification, reference being had to the accompanying drawing, forming a part thereof.

In the drawings:

Figure 1 is a top plan view of an airplane showing our new design;

Figure 2 is a front elevational view;

Figure 3 is a perspective view, and Figure 4 is a side elevational view thereof.

We claim:

The ornamental design for an airplane, substantially as shown.

KENNETH E. SMITH.
ALEXANDER G. TSONGAS.
